David Stuart of Philadelphia Pa.
Assignor to
W. P. Grefson & Co. of Philadelphia aforesaid.
Letters Patent No 678. Dated Nov 7th 1854.
(Ante-dated May 7th 1854)

The schedule referred to in these Letters Patent and making part of the same

To all to whom these presents shall come.

Be it known, that I, David Stuart of Philadelphia in the County of Philadelphia and State of Pennsylvania, have invented a new design for Stoves, and that the following is a full, clear, and exact description of the principle or character which distinguishes it from all other things before known, and of the usual, manner of making, modifying, and using the same, reference being had to the accompanying drawings, of which:

Fig. 1. is a perspective view of the egg stove entire, and —

Des. 678

Fig. 2, a side elevation of the same, and

Fig. 3, exhibits the design of the legs for the egg stove.

These drawings illustrate the design of the egg stove, which I claim as my invention and desire to secure by Letters Patent.
